Attorney.

UNITED STATES PATENT OFFICE.

MARY E. HARRIS, OF CAMDEN, NEW JERSEY.

SEWING-STAND.

SPECIFICATION forming part of Letters Patent No. 448,484, dated March 17, 1891.

Application filed June 30, 1890. Serial No. 357,227. (No model.)

To all whom it may concern:

Be it known that I, MARY E. HARRIS, a citizen of the United States, residing in the city and county of Camden, State of New Jersey, 5 have invented a new and useful Improvement in Sewing-Stands, which improvement is fully set forth in the following specification and accompanying drawings.

My invention relates to improvements in 10 sewing-stands, and has for its object a device whereby the articles in ordinary use in sewing may be conveniently assembled and held in place, so as to be of easy access for use when desired; and for this purpose it consists, first, of a table with a handle formed of 15 wire having an upper twisted portion with hooks laterally extending from the same; second, of a table with a pin-cushion, &c., provided with a standard and a drawer, the 20 lower end of said standard extending below said table and within the drawer, forming a stop and preventing removal of the said drawer from the table; third, of the combination and arrangement of the several parts, as 25 will be more fully hereinafter set forth.

Figure 1 represents a perspective view of a sewing-stand embodying my invention. Fig. 2 represents a transverse section thereof.

Similar letters of reference indicate corresponding parts in the two figures.

Referring to the drawings, A designates a stand or table having the drawer B therein and provided with a handle C, composed of two pieces of wire, each of which is connected 35 with the stand at one end, as at D, the said pieces being twisted together for a portion of their length, as shown, so as to form a strong and firm or rigid central portion for the handle, the inner ends of the pieces projecting 40 from the twisted portions being bent up, thereby forming the hooks E, adapted to support a pair of scissors F or other article thereon. Connected with the stand A are a number of pins or studs F', each of sufficient length to 45 be adapted to hold thereon one or more spools of thread G, as desired.

H designates a thimble-holder, shown in the drawings as of cup-and-saucer form, but which may be of any shape, so that it will retain the thimble when placed thereon.

A pin-cushion support is composed of a standard J, which is secured to the table A, the said standard being provided with the socket K, to which the cushion L is fastened 55 in any suitable manner and which is rotat-

ably secured to said stand by means of a screw M. By having the cushion rotatable all parts thereof can be brought into easy access of the user without turning the stand.

On the under side of the stand A and within 60 the drawer B, which latter is designed for holding needles, &c., is a pin N, adapted to abut against the rear of the drawer when the same is drawn out, so as to prevent its removal from the stand. In the drawings the 65 pin is shown as a continuation of the lower end of the standard, and it is preferable to so construct it.

The legs P on the corners of the stand permit the opening and closing of the drawer, as 70 well as support the said standard and contents.

It will be seen that a device constructed as described will readily and effectually serve the purpose designed, and, being simple in its 75 parts, can be made at little cost, and readily repaired.

Having thus described my invention, what I claim as new, and desire to secure by Letters Patent, is—

1. A sewing-stand comprising a table with a handle formed of wire, the upper twisted portion of the latter having hooks laterally extending from the same, substantially as and for the purpose set forth.

2. A sewing-stand comprising a table with a handle having a re-enforcing piece of material applied thereto, the ends of the said re-enforcing piece terminating in hooks extending laterally from the side of the handle, substantially as described.

3. A sewing-stand having a table provided with a handle composed of two pieces of wire, one end of each piece being secured to the stand, and the said pieces being twisted together, forming a central handle portion and having the free ends forming hooks, substantially as described.

4. A sewing-stand having a table with a standard thereon supporting a pin-cushion and provided with a drawer, the lower end of said standard extending below said table and within the drawer, forming a stop and preventing the removal of the said drawer from the table, substantially as described.

MARY E. HARRIS.
